GOVERNOR VALVE MECHANISM

Otto Lutherer, Solon, Ohio, assignor to The North American Manufacturing Company, Cleveland, Ohio, a corporation of Ohio

Application July 3, 1939, Serial No. 282,637

4 Claims. (Cl. 158—119)

This invention relates to valve mechanism for controlling the flow of fuel gas to gas burners, and more particularly relates to a shut-off attachment for zero pressure control valve mechanism.

In the supply of fuel gas to burners the gas is frequently supplied at zero or atmospheric pressure by means of a zero pressure governor valve. One difficulty with such governors has been that when the supply of air under pressure to the burner is abnormally reduced or is cut off, the zero governor valve does not completely close, or at best, it is held to its seat by zero pressure. Consequently any slight variation in pressure, such as by increase in suction produced by the Venturi or inspiration effect at the burner, is likely to produce gas leakage through the valve, with enough gas flowing either to overshoot the temperature to be attained or to make the operation hazardous, as with unfired semi- or full muffled furnaces.

One object of the invention is to provide improved valve mechanism for use in connection with zero pressure governor devices, and in which mechanism, when the air supply is abnormally reduced or is cut off or fails, the gas governor valve is held to its seat by positive pressure sufficient to prevent any leakage or escape of gas through the valve, and in which, during normal operation, with the air pressure turned on, the said positive holding pressure is completely eliminated or is made non-effective, so that it exerts no influence upon the usual pressure governing functions or operations of the controlling valve mechanism.

A further object of the invention is to provide an arrangement of this kind which is automatic in operation, requiring no attention whatever from the operator, but which nevertheless is reliable and dependable for the performance of its duty under all conditions.

A further object of the invention is to provide an arrangement of the kind described, which, in case of abnormal reduction in or failure of air pressure, automatically shuts off the gas supply without attention by the operator.

Further objects of the invention are in part obvious and in part will appear more in detail hereinafter.

In the drawing, Fig. 1 is a diagram, conventionally illustrating in section one suitable form of burner and mixer with my improved valve mechanism applied for the control of the gas supply thereto, the valve mechanism being shown in sectional elevation;

Fig. 2 is a detail view, corresponding to Fig. 1, and illustrating a modification.

While the invention may be applied to any form of burner, the drawing, for purposes of illustration and in no sense of limitation, show the invention applied to a burner mixer of the form shown, described and claimed in a prior application Serial No. 264,410 for Gas and air mixer for burner, filed March 27, 1939, jointly by myself and Charles E. Sladky, to which reference may be had for a more complete description, if desirable or necessary. The burner mixer comprises a hollow casing or body, generally indicated at 1, communicating with an air supply pipe 2 and a gas supply pipe 3. The air is delivered to an orifice 4, beyond which the mixture of gas and air flows through the throat 5 to a mixing chamber 6 from which the mixture is supplied to the hollow member 7 forming part of or connected to the burner. In burners of this kind there is a Venturi effect, with the production by the stream of flowing air of a suction or vacuum effect, with a consequent tendency to inspirate or draw in the gas from the gas supply pipe. The effect of the mixer and burner therefore is to reduce the pressure or increase the suction in the gas supply pipe.

Referring to the control valve mechanism shown in Fig. 1, said mechanism includes a hollow valve body 10 connected in the gas supply pipe 3 and having supply and discharge chambers 11, 12, with the flow of gas controlled by a valve 13 carried by a stem 14.

Attached to the top of the valve body is a chambered diaphragm casing 15, in which is a movable abutment, such as a diaphragm 16, fastened to the valve stem and carried by a support and guide 17 fixed to said stem and working loosely in an opening in the casing. A diaphragm 18, the area of which is small and whose effect is therefore negligible, is attached to the valve stem and seals or closes off communication from the gas supply chamber 11 to the chambers within casing 15. A small opening, such as that through a pipe 19, however, establishes communication from the lower chamber 20 to the outlet or discharge chamber 12 of the valve casing.

Chamber 21, above the diaphragm 16, is vented to atmosphere by way of a small port 22, and in a tubular extension 23 of the diaphragm casing is located an adjustable light loading tension spring 24 connected at its lower end to the valve stem and at its upper end to a threaded rod 25 provided with an adjusting nut 26, access to which may be secured by removing the threaded cap 27. The loading spring 24 is designed to have sufficient strength or force to almost exactly support the weight of the movable parts to which it

is attached, including the valve, its stem, and the diaphragms, when the valve is closed upon its seat, and the strength of the spring may be brought to such value by proper adjustment of the nut 26, as will be obvious. When said spring is properly adjusted, therefore, the weight of the valve stem, diaphragms, etc., is eliminated and may be disregarded.

Below the valve, the valve casing supports a suitable servomotor, shown as including a movable differential pressure operated abutment, such as a diaphragm 31, enclosed within a second hollow casing 30 attached to the main valve casing 15, said diaphragm being attached to a rod or stem 32 passing loosely through a guide 33 and entering the gas outlet chamber 31. Said rod is free of connection with the valve stem, but is axially aligned therewith and is directly below the same.

The chamber within casing 30 above the diaphragm 31 communicates either by way of a small port or around the valve stem with the gas outlet chamber 12. The chamber beneath diaphragm 31 communicates by way of a pipe 34 and valve 35 with the air supply pipe 2 on the upstream or supply side of a hand operated controlling valve 36 in said air pipe. Pipe 34 also communicates with atmosphere by way of a bleed cock or valve 37, which normally is left open.

38 indicates conventionally a mechanical connection, such as a link, between the handle of valves 35 and 36 so arranged that said valves always operate in opposition. That is to say, the two valves are operated manually but always conjointly, the arrangement being such that always when valve 36 is open valve 35 is closed, and vice versa.

The valve mechanism described operates as follows:

Air pipe 2 and gas pipe 3 of course individually may be provided with their own main shut-off valves, not shown. Let us assume that said main valves are wide open, with the supplies of both air and gas turned on, that the burner is ignited, and that the system is therefore in normal operation.

Valve 36, of course, is open, and, consequently, should remain open. Consequently valve 35 is closed. As a result, the chamber beneath diaphragm 31 is open to atmosphere through the bleed cock 37. Said diaphragm 31 is therefore subject on its lower surface to atmospheric pressure and upon its upper surface to approximately the same pressure, to-wit, the gas pressure in chamber 12, through which gas is flowing on its way to the burner. Diaphragm 31 and rod 32 therefore have dropped by their own weight and are in their lowermost position, with the rod 32 entirely out of engagement with and ineffective upon the valve stem. The valve is therefore subject to the inspiration or suction effect at the burner mixer, with gas flowing through the valve to said mixer. The valve operates as a zero pressure governor, and the cross connection between valves 35, 36, with the bleed cock 37, may be regarded as means operatively connected with the supplemental servo motor for positively rendering it ineffective or inoperative when the zero pressure governor valve is operating during normal gas flow. With no flow of gas, valve 13 is closed, and lies in contact with its seat, being held there by spring 24, but without pressure. Any demand for gas reduces the pressure in the outlet chamber 12, unbalances the forces effective upon the valve, and opens the valve propor-

tionately, with a consequent flow of gas. As the suction effect increases the valve opens wider and wider, and as it is reduced the valve moves toward closed position. But in any event, the gas pressure in chamber 12 is approximately atmospheric, so that diaphragm 31 remains depressed. During normal operation of the valve mechanism therefore, it functions like any ordinary zero pressure governor valve, permitting gas to flow in accordance with the varying demand of the Venturi nozzle in the mixer.

If the flow of air to the mixer and burner is abnormally reduced, such as by closing valve 36, the same operation, through the mechanism 38, opens valve 35. Full air pressure, considerably above atmospheric, now becomes effective through the pipe 34 upon the lower face of servomotor diaphragm 31, the orifice through the bleed port 37 being so small that its venting effect is negligible. The pressure beneath diaphragm 31 therefore now becomes sufficient to preponderate over the pressure in chamber 12, so the diaphragm 31 and the rod 32 are elevated. The upper end of said rod engages the valve stem 20 and either closes it upon its seat or holds it to its seat if it is already there. Therefore, when the air supply is cut off the former zero pressure governor valve now becomes a shut-off valve positively held to its seat by the servo motor diaphragm, and more particularly by the preponderating effect thereon of the air pressure in pipe 2 on the inlet side of valve 36. Consequently there is no possibility of escape or leakage of gas through the gas valve such as might overshoot the temperature to be obtained, or entail hazard, as in the case of muffle furnaces.

Fig. 2 illustrates a modification in which the lower servomotor diaphragm 31a, on its lower face, is subject not to the pressure of the air supplied through pipe 2, but to the pressure of atmosphere by way of a small port 40, and to the pressure of a compression loading spring 41, while on its upper face said diaphragm 31a is subject to the pressure of the air supply pipe, on the downstream side of its main valve (not shown) by way of pipe 42. Connection between the upper chamber 43 of the diaphragm casing and the outlet chamber 12 of the valve casing is shut off by a supplemental small sealing diaphragm 44.

With this arrangement, as long as air flows normally to the mixer and burner through the air supply pipe 2, the pressure within said pipe is effective in chamber 43 and preponderates over air pressure and the effect of spring 41 beneath diaphragm 31a, thereby positively holding said diaphragm and the rod 32a depressed, or in their ineffective positions. The valve, therefore, functions as a zero pressure governor valve in the same manner as in the form before described.

However, when the air supply is cut off, by closure of the main valve (not shown) in pipe 2, or should said air supply fail or should it be otherwise abnormally reduced for any reason independent of operator control of the pipe 2, the compressed air supply through pipe 42 to chamber 43 also fails or is abnormally reduced. As a result servomotor diaphragm 31a now is subject on both of its faces to atmospheric pressure and on its lower face also to the effect of loading spring 41, so that the preponderating pressure is below said diaphragm. It therefore either rises and applies the rod 32a to the lower end of the valve stem and closes said valve, or it holds it closed if it is already closed. There-

fore, when there is no air supplied to the burner the valve operates as a positive shut-off valve for the gas supply, with the positive pressure of the servomotor holding the valve to its seat, as in the first form described.

The arrangement just described, therefore, operates in generally the same manner as the form shown in Fig. 1, but has the added advantage that the valve closes automatically and is held closed, in case of abnormal reduction in or failure of air pressure beyond the knowledge of the operator.

What I claim is:

1. In apparatus for supplying a mixture of gas and air to a burner and including a burner and the gas and air supply pipes therefor, the combination of a zero pressure governing valve in the gas supply pipe arranged upon flow of both gas and air to regulate the gas flow in accordance with the suction effect of the burner, differential pressure operated movable abutment means so arranged and mounted that when its abutment moves in one direction it closes said valve to positively shut off gas flow and when moved in the opposite direction it releases said valve for free movement, and means associating said abutment means with the air supply pipe in such manner as to move said abutment in the valve releasing direction when normal air flow to the burner is permitted and to move said abutment in the valve closing direction when the air flow is abnormally reduced.

2. In apparatus for supplying a mixture of gas and air to a burner and including a burner and the gas and air supply pipes therefor, the combination of a zero pressure governing valve in the gas supply pipe arranged upon flow of both gas and air to regulate the gas flow in accordance with the suction effect of the burner, differential pressure operated movable abutment means so arranged and mounted that when its abutment moves in one direction it closes said valve to positively shut off gas flow and when moved in the opposite direction it releases said valve for free movement, means for supplying a substantially constant pressure to one face of said abutment means, and means for applying the pressure of the air supply to the opposite face of the abutment means, said means being so arranged that the abutment is biased in the valve releasing di-

rection when normal air flow is permitted and is biased in the opposite direction when air flow is abnormally reduced.

3. In apparatus for supplying a mixture of gas and air to a burner and including a burner and the gas and air supply pipes therefor, the combination of a zero pressure governing valve in the gas supply pipe arranged upon flow of both gas and air to regulate the gas flow in accordance with the suction effect of the burner, differential pressure operated movable abutment means so arranged and mounted that when its abutment moves in one direction it closes said valve to positively shut off gas flow and when moved in the opposite direction it releases said valve for free movement, said abutment during normal air flow to the burner being sensitive upon its valve releasing face to pressure of the gas flowing to the burner and upon its opposite face to a lesser pressure, and means arranged when the air supply to the burner is cut off to apply to said opposite face the pressure of the air supply, whereby during normal air flow to the burner the valve is fully released and when the air supply to the burner is cut off the valve is positively closed and serves to fully shut off gas flow.

4. In apparatus for supplying a mixture of gas and air to a burner and including a burner and the gas and air supply pipes therefor, the combination of a zero pressure governing valve in the gas supply pipe arranged upon flow of both gas and air to regulate the gas flow in accordance with the suction effect of the burner, differential pressure operated movable abutment means so arranged and mounted that when its abutment moves in one direction it closes said valve to positively shut off gas flow and when moved in the opposite direction it releases said valve for free movement, said abutment being sensitive upon its valve closing face to the pressures of atmosphere and a spring, and means for applying to its opposite face the pressure of the air flowing to the burner, whereby during normal air flow to the burner the valve is fully released and upon abnormal reduction in air flow the valve is positively closed and serves to fully shut off gas flow.
